UNITED STATES PATENT OFFICE.

FRANK J. VAN ARNHEM, OF LAKESIDE, OHIO.

DOOR-CLOSING DEVICE.

Application filed September 24, 1923. Serial No. 664,481.

To all whom it may concern:

Be it known that I, FRANK J. VAN ARNHEM, a citizen of the United States, and a resident of Lakewood, county of Cuyahoga, 5 and State of Ohio, have invented a new and useful Improvement in Door-Closing Devices, of which the following is a specification, the principle of the invention being herein explained, and the best mode in 10 which I have contemplated applying that principle so as to distinguish it from other inventions.

This invention relates to a door-closing device. More particularly it comprises a 15 simple appliance to be attached to the inside face of a door and the adjacent face of its supporting structure on the side of the door opposite to the hinges thereof and serving to swing the door to its closed position.

20 While of general application the device is of particular utility in connection with the doors of automobiles.

It is well known that much difficulty has been encountered in preventing injury to 25 the doors of automobiles when passing into and out of the garage or through other narrow passageways. This is particularly true in connection with closed cars and it has been sought to avoid the difficulties, to some 30 extent, by swinging the doors from the forward side of the car body rather than upon the rearward position thereof. However, when the doors are swung from the forward side of the frame if the car is backed out 35 of the garage while the door is in open position the door will be seriously damaged. It has, therefore, been found desirable to provide a door-closing means for swinging the doors to their closed position when they 40 are not positively held in open position.

It is common practice to provide a check strap on the inside of doors to prevent their 45 being swung outwardly to too great an extent. This strap usually comprises a heavy fabric material securely fastened at each of its ends to bracket members, secured respectively to the door and its adjacent supporting member. As will be hereinafter pointed out, this invention combines with a door 50 check strap resilient means for swinging the door to closed position.

To the accomplishment of the foregoing and related ends, the said invention, then, 55 consists of the means hereinafter fully described and particularly pointed out in the claims.

The annexed drawing and the following description set forth in detail certain mechanism embodying the invention, such disclosed means constituting, however, but one 60 of various mechanical forms in which the principle of the invention may be used. In said annexed drawing:—

Fig. 1 is the front elevation of the door-closing device. 65

Fig. 2 is the end elevation thereof and;

Fig. 3 is a horizontal sectional view of the device shown in Fig. 1, showing the application thereof to the door of an automobile. 70

As is clearly illustrated in the drawing a pair of bracket members 1, 2, are attached respectively to the door, 3, and frame, 4, by means of screws, 5, or other suitable fastening devices. Such supporting elements are 75 preferably provided with a central cylindrical section, 6, of reduced diameter, held in spaced relation to the adjacent surface to which said brackets are attached, by means of angular terminal elements, 7, which are 80 tapered outwardly adjacent the cylindrical central portions, and serve as lateral guides for the fabric and rubber strap elements presently to be described.

The door is supported upon its adjacent 85 frame member by means of suitable hinges, 8, of standard construction.

Upon the cylindrical portions of the brackets a pair of continuous bands are supported. These bands comprise an outer band, 90 11, of fabric, preferably of heavy inelastic fabric, and a continuous band, 12, preferably of rubber or other elastic material. Band 12 is located immediately within the band 11 and is preferably placed under a 95 certain degree of tension when the device is applied to the door and its supporting structure.

Thus, in applying the device to an automobile the brackets are attached in vertical 100 position to the inside of the car adjacent the door and to the inner side of the door with sufficient space between them to insure a certain degree of tension upon the rubber strap. When the door is opened to approximately an angle of 90 degrees to the body of the car the fabric strap will be brought firmly against the cylindrical portion of the two bracket members and prevent further outward movement of the door. The rubber 110 strap at this time will be placed under an increasing degree of tension and will tend

2
to swing the door to closing position as soon as it is released.

The elasticity of the inner strap is such that the door will be swung to closed position with a slow swinging motion which will not injure anyone coming into contact with the moving door. Should it be desired to vary the tension upon the device this may be readily accomplished by changing 10 the position of the brackets or by substituting different lengths of fabric and elastic straps upon said brackets.

The device is of extremely simple construction and may be readily applied to automobiles in general use. When so applied, if desired, the usual door check straps may be omitted and such device used in lieu thereof.

Other forms may be employed embodying 20 the features of my invention instead of the one here explained, change being made in the form or construction, provided the elements stated by any of the following claims or the equivalent of such stated elements be 25 employed.

I therefore particularly point out and distinctly claim as my invention:—

1. A combined check and closing device for doors comprising a pair of bracket ele-

ments attached respectively to a door and 30 its supporting member upon the side opposite the hinges, an outer and inner loop engaged over said brackets, said outer loop being formed of inelastic material of greater length than the normal space between said 35 brackets when the door is in closed position, and said inner loop being formed of elastic material and being placed under tension when said door is in open position.

2. A combined check and closing device 40 for doors comprising a pair of bracket elements each having cylindrical central portions and angular terminal members adapted to space said central portions from the surface to which said brackets are attached, an outer and inner loop engaged over said cylindrical portions of said brackets said outer loop being formed of inelastic fabric material of greater length than the normal 45 space between said brackets when the door is in closed position, and said inner loop being formed of elastic material and being placed under tension when said door is in open position.

Signed by me this 19th day of September, 50
1923.

FRANK J. VAN ARNHEM.
